UNITED STATES PATENT OFFICE.

DAVID M. IRELAND, OF WATERBURY, CONNECTICUT, ASSIGNOR OF ONE-HALF TO HENRY A. MATTHEWS, OF SAME PLACE.

DESIGN FOR A WAITER.

SPECIFICATION forming part of Design No. 16,406, dated December 8, 1885.

Application filed October 19, 1885. Serial No. 180,357. Term of patent 3½ years.

To all whom it may concern:

Be it known that I, DAVID M. IRELAND, of Waterbury, in the county of New Haven and State of Connecticut, have invented a new Design for Waiters; and I do hereby declare the following, when taken in connection with accompanying drawings and the letters of reference marked thereon, to be a full, clear, and exact description of the same, and which said drawings constitute part of this specification, and represent, in—

Figure 1, a face view of the waiter; Fig. 2, a section through one corner on line *x x*; Fig. 3, a section through the same corner at right angles to Fig. 2 and on line *z z*.

This invention relates to a design for that class of waiters which present a flat surface with a turned-up edge or margin, *a*; and the design consists in the turned-up edge concave upon the inside from the flat surface upward, the corners rounded, and the rim at the corners convex or reversely curved upon the inside.

As represented in the drawings, the waiter is square, its four corners or angles rounded.

The margin or edge of the waiter is curved upward—that is, presents a concave surface upon the inside extending from the flat bottom upward. At the angles or rounded corners the inner surface is curved reversely to that of the general margin, presenting a convex surface, as at *a*, the curve on the convex surface dying out in the adjacent concave surface of the general margin.

I claim—

The herein-described design for waiter, presenting rounded corners with a margin around the sides, presenting a concave surface upon the inside extending from the flat bottom upward, the rounded corners presenting a convex or reversely curved surface upon the inside, the said convex surface dying out in the adjacent concave surface of the margin, as shown in the accompanying illustrations.

D. M. IRELAND.
